UNITED STATES PATENT OFFICE.

FRED L. WILKE AND WILLIAM BURNS, OF CHICAGO, ILLINOIS.

DESIGN FOR A VENDING-MACHINE CASING.

Application filed October 24, 1925. Serial No. 15,248. Term of patent 3½ years.

To all whom it may concern:

Be it known that we, FRED L. WILKE and WILLIAM BURNS, citizens of the United States, residing at Chicago, in the county of Cook and State of Illinois, have invented a new, original, and ornamental Design for Vending-Machine Casings, of which the following is a specification, reference being had to the accompanying drawing, forming part thereof.

The figure is a perspective view of a vending machine casing, showing our new design.

We claim:

The ornamental design for a vending machine casing, as shown.

In testimony whereof we affix our signatures.

FRED L. WILKE.
WILLIAM BURNS.
